UNITED STATES PATENT OFFICE.

ALFRED SHUTTLEWORTH, OF LONDON, ENGLAND, ASSIGNOR OF ONE-HALF TO FRANK SMITH, OF LONDON, ENGLAND.

DOMESTIC WASHING BOARD.

Application filed March 6, 1923. Serial No. 623,185.

To all whom it may concern:

Be it known that I, ALFRED SHUTTLEWORTH, a subject of the King of Great Britain and Ireland, residing at London, N. W. 5, England, have invented Improvements in Domestic Washing Boards (for which I have filed application in Great Britain, Dec. 19, 1921, No. 34,099), of which the following is a specification.

10 The object of this invention is to provide a cheap and simple portable device for facilitating the washing and wringing of linen and other articles or material and with this object in view there is combined with a 15 washing board a pair of wringing rollers both mounted directly in the frame of the board and adapted to be rotated by means of a crank, wheel or equivalent. Such a device may also be provided with a support 20 for holding the combined washing board and wringer steady in an upright or conveniently inclined position clear of the side of the wash tub, bath or other vessel, the 25 said support being so arranged as to serve to guide the objects being wrung to the outside of the tub in which the board is positioned.

The accompanying drawings illustrate a 30 combined washer and wringer embodying the present improvements, Fig. 1 being a perspective view of the whole, Fig. 2 a partial elevation partly in section, and Fig. 3 a detail of a modification hereinafter described. Fig. 4 is a detail perspective view 35 of a detail hereinafter described. Fig. 5 is a miniature vertical section of a part of a wash-tub showing my washboard positioned therein.

40 a, b are upright side members and c a horizontal top member which together form a rigid frame both for the washing board and for the wringer. The body d of the washing board, which may be made of wood, or other suitable material, is located between the side members a and b in the usual 45 way, but near the top a gap is left, which is occupied by a pair of rollers e and f having spindles j, k journaled in the side members a and b in brass or other suitable plates e^1 50 formed with bearings for the spindles and fitted in or attached to the side members.

One of the rollers, the upper roller e , for instance, is provided with a crank g for rotating it.

55 Squeezing or wringing pressure may be

applied to one or both of the rollers e, f preferably through the roller spindle bearings by means of suitable metallic springs l or by rubber springs or equivalent devices, not shown, which devices may in some instances be mounted in the side members a, b , as shown in Fig. 2, or may be protected by being enclosed, as in brass tubes m , as shown in Fig. 3. To place the tubes m in position holes of suitable diameter are bored downwards for a suitable distance through the side members a and b , and after the tubes have been inserted therein the upper parts of the holes are closed by means of wooden plugs. A plate h is hinged to the spindle k of the lower roller f , and may be provided at or near the edge remote from the rollers with means such as a bent wire i adapted to engage with the edge of a bath or the like, to serve the double purpose of keeping the 75 whole apparatus while it is being used, steady in an approximately upright position or at a desired inclination clear of the side of the tub and of guiding the objects that are being wrung from the rollers e, f 80 out of the bath or the like. This plate h is mounted below the contacting faces of the rollers and has a width equal to the length of the rollers, and by reason of the hinged connection to the spindle k the plate has a 85 pivotal motion up and down at its free end.

What I claim is:—

1. In combination with a washboard having a frame, a pair of wringing rollers mounted in the frame of the board above the rub-surface thereof, and a plate having a width substantially equal to the length of the rollers and connected to the board below the contacting faces of the rollers, the free end of said plate being provided with means for engaging the upper edge of a tub to thus permit said plate to be used as a prop for the board and also as a clothing-guide or chute.

2. The combination with a washing board having a frame of a pair of wringing rollers both having spindles mounted directly in the frame of the board and adapted to be rotated, a crank on one of said spindles and a member pivoted to one of the said spindles and comprising a plate having means for attaching its free end to a tub adapted to support the washing board and to serve as a guide for the wrung objects.

3. The combination with a wash-board

having a frame of a pair of wringing rollers mounted in the frame of the board above the rub surface thereof, and a plate having a width substantially equal to the length of the rollers and connected to the board at a point below the contacting faces of the rollers, said connection being a pivotal one to permit the plate's free end to swing up and

down, said free end being provided with means for engaging the upper edge of a tub to thus permit said plate to be used as a prop for the board and also as a clothing guide or chute.

Signed at London, England, this 23rd day of February, 1923.

ALFRED SHUTTLEWORTH.
